ATTORNEY

UNITED STATES PATENT OFFICE.

HORACE T. THOMAS, OF LANSING, MICHIGAN.

GRINDING PROCESS.

1,252,509.

Specification of Letters Patent. Patented Jan. 8, 1918.

Application filed July 7, 1916. Serial No. 107,889.

To all whom it may concern:

Be it known that I, HORACE T. THOMAS, a citizen of the United States, residing at Lansing, county of Ingham, State of Michigan, have invented a certain new and useful Improvement in Grinding Processes, and declare the following to be a full, clear, and exact description of the same, such as will enable others skilled in the art to which it pertains to make and use the same, reference being had to the accompanying drawings, which form a part of this specification.

My invention relates to an improved process of grinding and an apparatus for use in the performance of said process and a special object of my improvements is to provide an improved method of grinding integral-splined shafts to be used in the change speed gearing for automobiles.

I secure this object in the process and apparatus hereinafter described and illustrated in the accompanying drawings in which:

Figure 1 is an elevation of an apparatus by which my invention is, in part, performed; and

Fig. 2 is a perspective view of a section of a shaft such as is ground by this improved process.

30 *a* is a driven shaft and *b* is a gear wheel rigidly secured thereon. *c* is a cam rigidly secured upon the shaft *a*. *d* is a second gear wheel, its teeth engaging with the teeth of the gear wheel *b* so as to be driven thereby.

35 *k* is the shaft to be ground. This is secured coaxially with the wheel *d* so as to turn with said wheel.

e and *f* are arms of a bell-crank lever adapted to oscillate about the arbor *h*. *m*

40 is a grinding wheel secured to a spindle *i* bearing in the outer end of the arm *f*. The grinding wheel is rotated rapidly in the usual manner. *j* is a friction wheel bearing at *g* in the outer end of the lever arm *e*.

45 The wheel *j* bears against the surface of the cam *c* and the bell-crank lever *e f* is oscillated by said cam acting thereon through the friction wheel.

The shaft *k* is shaped roughly to form, **50** having the splines *k¹* *k²* *k³* integral therewith and extending radially therefrom. The shaft is cut deeper than elsewhere adjacent to the splines *k¹*, as indicated, thus forming grooves *k⁴* having their inner walls inside **55** of the other surfaces of the shaft. The shaft is then heat-treated which leaves it

approximately in shape but requiring it to be ground to rectify it and accurately finish its surface.

The cam *c* is so formed that it shall hold **60** the grinding wheel *m* against the salient cylindrical surface between adjacent grooves *k³* and between the splines *k²*. When the shaft has turned such cylindrical surface past the grinding wheel *m* the bell-crank **65** lever *e f* is acted on by the cam *c* to draw said wheel farther from the center of the shaft *k* and into position to permit the passage of a spline and to grind the outer cylindrical surface thereof. As each spline **70** passes under the grinding wheel *m* in the rotation of the shaft *k*, its outer surfaces is ground.

Thus the main bearing surface *k⁴* between adjacent grooves *k³* and between the **75** splines *k²* are accurately finished to the required size, and the radial distance between these surfaces and the outer cylindrical surface of the spline *k²* is definitely and accurately fixed and the outer surfaces of the **80** splines are ground.

What I claim is:

1. The process of grinding splined-shafts consisting in shaping said shafts with depressions below the rest of the surface **85** thereof adjacent to said splines, rotating said shaft about its longitudinal axis and applying a grinding wheel, rotating about an axis parallel to the axis of said shaft, to the surface intermediate said grooves and **90** said splines to finish said surface, drawing said grinding wheel away from said shaft as one of the splines pass thereunder and again moving said grinding wheel toward the shaft to engage the next bearing surface. **95**

2. The process of grinding splined-shafts consisting in forming said shafts with grooves below the rest of the surface of said shaft, adjacent to the splines leaving a salient cylindrical bearing surface between **100** said grooves and splines, rotating said shaft in front of a grinding wheel and varying the position of said grinding wheel relative to said shaft by means of a cam so that it shall pass over said cylindrical surface to **105** grind the same and to permit the passage of the splines.

3. The process of grinding splined-shafts consisting in forming said shafts with grooves below the rest of the surface of said **110** shaft adjacent to the splines leaving a salient cylindrical bearing surface between

said grooves, rotating said shaft in front of a grinding wheel and varying the position of said grinding wheel relative to said shaft by means of a cam so that it shall pass over said cylindrical surface to grind the same and to permit the passage of the splines, and so that it shall pass over and finish the outer surfaces of said splines.

4. The process of grinding a splined shaft
10 consisting in continuously rotating said shaft, in front of a grinding wheel, varying the position of said grinding wheel to act on the surface intermediate said splines and to permit the passage of said splines.

15 5. The process of grinding a splined shaft consisting in continuously rotating said shaft, in front of a grinding wheel, varying the position of said grinding wheel to act on the surface intermediate said splines and
20 to permit the passage of said splines, and to act upon the outer surface of said splines to finish the same.

6. A process of grinding a splined shaft consisting in continuously rotating said shaft about its longitudinal axis in front 25 of a grinding wheel and automatically varying the position of said grinding wheel to act on the surface intermediate said splines and to permit the passage of said splines, said grinding wheel rotating about an axis 30 parallel to the axis of said shaft.

7. The process of grinding a splined shaft consisting in rotating said shaft about its axis providing a grinding wheel adapted to be moved toward and away from said shaft 35 and acting upon said grinding wheel by a cam to vary its position to grind the surfaces of said shaft intermediate said splines, and to permit the passage of said splines, and to grind the outer surfaces of said 40 splines.

In testimony whereof, I sign this specification.

HORACE T. THOMAS.
